UNITED STATES PATENT OFFICE.

NAPOLEON JOSEPH COTÉ, OF MONTREAL, QUEBEC, CANADA.

COMBINATION FURNITURE.

No. 891,040.

Specification of Letters Patent.

Patented June 16, 1908.

Application filed September 16, 1907. Serial No. 392,965.

To all whom it may concern:

Be it known that I, NAPOLEON JOSEPH COTÉ, a subject of the King of Great Britain, residing at the city and district of Montreal, Province of Quebec, Canada, have invented 5 certain new and useful Improvements in Combination Furniture; and I do hereby declare that the following is a full, clear, and exact description of the invention, such as 10 will enable others skilled in the art to which it appertains to make and use the same.

The present invention relates to combination furniture, and more particularly to the folding bed type of furniture wherein a wardrobe, 15 chiffonnier, bureau, closet or the like is combined with a bed, the two constituting one structure adapted for a two-fold purpose and each serving its particular purpose when the whole structure is in one or another 20 of its several positions.

Broadly speaking, the invention comprises a combined bed and wardrobe, and a casing adapted to receive the combination piece together with suitable connections between 25 the combination piece and the casing whereby the same may be raised or lowered, and when in its raised position will lie snugly within the casing and devices adapted to assist both in raising and lowering the combination piece.

In order to more clearly disclose the construction, use and operation of this invention, reference should be had to the accompanying drawings forming part of the present 35 invention, wherein like reference characters designate similar parts in the several views.

In the drawings:—Figure 1 is a front view of the device in its extreme closed position, showing it adapted for use as a wardrobe; 40 Fig. 2 is a side view of the device showing the same in full lines, in its lowered position, and in dotted lines in its first position, just preliminary to being lowered; Fig. 3 is a detail on line 3—3 of Fig. 4 showing the spring retarder; Fig. 4 is a detail on line 4—4 of Fig. 3; and, Fig. 5 is a detail on line 5—5 of Fig. 4.

The invention as a whole comprises a suitable casing 1 adapted to completely and 50 snugly receive a combination piece comprising a bed 2 and a wardrobe 3 which in the preferred form are securely fastened together to form substantially one piece, the wardrobe being accessible and adapted for use 55 when the piece as a whole is raised and fitted within the casing, and the bed being accessi-

ble and ready for use when the piece is in its lowered position; all as will readily appear from Figs. 1 and 2 respectively. This combination piece is pivotally mounted at 4 on 60 arms 5, the opposite ends of which are pivotally connected to the inner faces of the casing 1 as at 7.

In order to prevent the combination piece falling with the full force of its weight, a retarding device is used, the operation and construction of which will be later disclosed. This retarding device comprises a rod 8 carried by brackets 9, or the like, which are suitably secured to the inside of the casing 1. 65 In the preferred form this retarder is mounted in brackets on the bottom of the casing, though of course it may be mounted on the side or in other positions, provided it is so positioned that its function will be the same. 70 On the rod 8 is loosely mounted a spring 10 adapted to be compressed between yokes 11, mounted to travel freely on said rod. These yokes are pivoted to the arms 5 at points diametrically opposed as shown in Fig. 3. As 75 will be clear from Fig. 3, as the combination piece is lowered to the position of Fig. 2 the yokes 11 will approach one another and the spring 10 will be compressed. Of course, the reaction of the spring as it is gradually compressed will increase and its resulting retardation of the same 5 and the combination piece mounted thereon will likewise gradually increase. Thus the maximum effect of the spring will be brought to bear at the lowest 80 position of the arm 5, as indicated by dotted lines in Fig. 3, and the minimum efficiency 85 when the arm 5 is in its highest position, as indicated in said Fig. 2, in full lines.

In order to allow free turning of the combination piece as a whole about the pivot point 7 preliminary to lowering the same, it is essential that a space be provided between the back of the casing 1 and the bed 2 at the moment it is desired to lower the 100 piece. It is also essential to make the casing 1 as small as possible and in order to accomplish both results, the pivotal connection 4 between the upper end of the arm 5 and the combination piece has been provided. Due 105 to this construction, as will appear from a comparison of Figs. 1 and 2, the device may first be pulled outward in the direction of the arrow (Fig. 2) a sufficient distance to permit it to be swung about the pivot 7 without 110 binding against the back of the casing 1. The distance of this outward movement is

limited by the post 12 with which the lower end of the bed contacts, and thus on continued movement of the same, the combined bed and wardrobe is tilted into a horizontal position, all as will clearly appear on reference to Fig. 2. This post 12 forms a support for one end of the piece while the opposite end is supported on the ornamental molding blocks 13 secured to the upper front edge of 5 the wardrobe. The space which is necessarily left between the lower end of the wardrobe and the bottom of the casing in order to permit free movement of the arms 5 and the turning of the piece as a whole, is filled, 10 when the piece has been moved to the position indicated in Fig. 1, by a drawer 14 adapted to slide on guides 15. These guides 15 it will be noticed also form additional supports for the posts 12, thus securing the posts more 15 rigidly in position.

20 The drawer when in position forms an absolute lock for the combination piece, thus completely preventing the same from being lowered or moved from a perfectly upright position, as will be readily understood.

25 A preferred form only of the device has been illustrated, and it is clear that many changes in the construction, operation and arrangement may be resorted to without in 30 any way departing from the field and scope of the present invention, and it is meant to include all such in the invention as described by the present application.

35 Having thus fully described my invention, what I claim as new and desire to secure by Letters Patent is:

40 1. Combination furniture of the character described, comprising a casing, arms pivotally mounted in said casing, a combination wardrobe and bed carried by said arms and adapted to be swung to a vertical position and completely inclosed within the casing, and a removable drawer adapted to be inserted in the casing below the combination

bed and wardrobe to lock the same in raised 45 position.

2. A retarding device for combination furniture of the character described comprising a rod, a spring mounted upon said rod, yokes adapted to slide upon said rod and connected 50 at diametrically opposed points to an arm, whereby the aforesaid spring is compressed upon movement of the aforesaid arms.

3. A retarding device for furniture of the character described comprising a rod, a 55 spring mounted thereon, an arm, and yokes connected to said arm and adapted to be moved toward each other and to compress said spring as said arm is moved.

4. A retarding device for furniture of the 60 character described comprising a rod, a spring mounted thereon, an arm, and yokes connected to said arm and adapted to compress said spring upon movement of the arm.

5. A retarding device for combination furniture of the character described, comprising a rod, a spring mounted upon said rod, a pivotally mounted arm, yokes adapted to slide upon said rod and to compress said spring, and connections between said yokes and said 65 arm whereby upon movement of said arm the yokes are moved and the spring compressed.

6. A retarding device for combination furniture of the character described, comprising a rod, a spring mounted upon said rod, a pivotally mounted arm, perforated yokes adapted to slide upon said rod and to compress said 70 spring, and pivotal connections between said yoke and said arms whereby upon movement of the said arm the yokes are moved and the 75 spring compressed.

In witness whereof I have hereunto set my hand in the presence of two witnesses.

NAPOLEON JOSEPH COTÉ.
